STEADY REST

Lloyd L. Babcock, Compton, Calif., assignor to
 The National Supply Company, Pittsburgh, Pa.,
 a corporation of Pennsylvania

Application March 16, 1938, Serial No. 196,178

13 Claims. (Cl. 82—39)

This invention relates to a new and improved steady rest of the type used in conjunction with machine tools, and is particularly directed to a device for guiding and supporting a work piece in a lathe or like machine.

In contemporary machine tool practice, certain classes of work require the use of a steady rest at various different positions relative to the work piece during the sequence of operations. It is frequently necessary to shift the position of the steady rest around some obstruction on the work piece. In the conventional type of steady rest, this operation is slow and cumbersome, and may even entail the removal of the work piece from the machine before the steady rest can be moved to a new position.

Accordingly, the principal object of this invention is to provide a steady rest which has greater flexibility in operation and which can be readily moved from and relocated upon its support without disturbing the work piece which it steadies.

Another object of this invention is to provide a steady rest having the general shape of an inverted U, which construction is adapted to straddle the work piece and thereby facilitate the operation of placing the steady rest in operative position.

Another object of this invention is to provide a steady rest composed of two supporting legs hingedly secured together, and a latch on the free end of each leg to releasably secure it to its support.

Another object of this invention is to provide a novel lock or latch on the steady rest so that it may be quickly secured or released from its support.

Other objects and advantages of this invention will be apparent from the following detailed description of a preferred embodiment thereof as illustrated in the accompanying drawing.

In the drawing:

Fig. 1 is a side elevation of a preferred embodiment of this invention shown in operative position upon the ways of a lathe.

Fig. 2 is a similar view of the steady rest showing how it may be removed from the lathe ways without disturbing the work piece.

Fig. 3 is an end view of the device as shown in Fig. 1.

Fig. 4 is a section view taken on the line 4—4 as shown in Fig. 1.

Fig. 5 is a sectional view taken on the line 5—5 as shown in Fig. 1.

Referring to the drawing, 1 indicates the body of the steady rest which is of the general shape

of an inverted U. The body 1 comprises sections 2 and 3 which are pivoted together at the pin 4 and which are adapted to engage a support at their lower ends. Each section 2, 3 has a depending extension or leg 5, 6 respectively, the lower ends of which are each provided with an inverted V guide 7 adapted to engage one of a pair of parallel ways 8. Three adjustable guides 9 are carried by the body 1 and are adapted to support and guide the rotatable work piece W in the usual manner. These guides are preferably positioned about the work piece W in the manner shown; i. e., equally spaced and with the uppermost in a substantially vertical position.

A releasable latch mechanism is provided on the lower end of each of the legs 5 and 6, and includes a pin 10 which carries a pair of latches 11 integrally connected by a bar member 12. Each latch has a hook portion 13 engageable with a shoulder 14 provided on the ways 8. The end portions 15 and 16 of each pin 10 which carry the latches 11 have the same axis of rotation, while the center portion 17 which is rotatably supported on the leg 5, is formed eccentric with respect to this axis. Rotation of the pin 10 by means of the head 18 tightens the latches against the shoulder 14 to lock the leg 5 to the way 8, and rotation in the opposite direction acts to release the lock and permit the latches 11 to be swung to their inoperative position, shown by the dotted lines in Fig. 1. The steady rest can then be removed from the ways 8.

In order to provide adequate strength and stiffness with a minimum of weight, the sections 2 and 3 are formed of a fabricated box construction. Accordingly, the face plates 19 are secured to and spaced apart by webs 20 to form integral members. The section 3 is bifurcated as shown at 21 while the section 2 is provided with a tongue 22 to form a close fit between the tongue 22 and lugs 23. The pin 4 projects through the tongue 22 and lugs 23 to form a rigid hinge connection. A non-circular section 24 on one end of the pin 4 is adapted to fit into a complementary recess 25 formed in one of the lugs 23 to prevent the pin 4 from turning. By tightening a nut 26 on the pin 4, the sections 2 and 3 can be clamped solidly together.

The adjustable guides 9 are arranged to slide radially of the work piece W within housings 27 carried on the sections 2 and 3. An adjusting screw 28 is rotatably mounted on an end-wall 29 of each of the housings 27 and engages threads formed within the guide members 9 to adjust the guides 9 radially of the work piece W. A slot 30 is formed in each of the guide members 9 through

which a locking pin 31 is passed. Tightening of the nut 32 on the pin 31 acts to secure the guide 9 in adjusted position.

The steady rest straddles the work piece W in its operative position with the legs 5 and 6 spaced as to form an opening 33 between them. When it is desired to remove the steady rest, or relocate it relative to the work piece W, the nut 26 is loosened and the latches 11 and 12 are released and swung to the position shown in dotted lines in Fig. 1. When the ways 8 are similar in shape and are of the common type illustrated in the drawing, it has been found that the steady rest can be removed from the ways 8 without disturbing the setting of the adjustable guides 9 and without removing the work piece W. This operation can be accomplished when the steady rest is of the approximate proportions illustrated and when the included angle X formed between the lower guides 9 is substantially greater than the included angle Y formed between the inside slopes 34 of the ways 8.

Under these conditions, when the steady rest is lifted by means of the member 35, the lower radial guides abut the work piece W, causing the sections 2 and 3 to pivot about the pin 4, and causing the lower ends of the legs 5 and 6 to move outwardly. This condition is shown in Fig. 2. After the lower ends of the legs clear the ways 8 completely, the legs continue to move outwardly until the work piece W passes between the lower guides 9. If necessary, the steady rest may be lifted until the work piece W passes out through the opening 33.

If the steady rest is relocated in a position where the work piece W has a diameter equal to that at its former position, it is only necessary to lower the steady rest so that the inverted V guides 7 come into contact with the lathe ways 8. Then, by turning the pins 10 to tighten the latch hooks 13, and by tightening the nut 26, the operation of relocating the steady rest is completed, without disturbing the work piece W or the setting of the guides 9. It is obvious that if the work piece W is of a different diameter, the setting of the adjustable guides must be changed.

Although I have shown and described a two-piece pivoted type of steady rest, it will be apparent that my invention is not limited to this construction, but is susceptible to modifications, wherein certain features of my invention might be embodied in a steady rest having more than two sections, or constructed as a one-piece yoke, with legs or extensions adapted to straddle the work piece and be secured to supports. Further, I wish it to be understood that I am aware that my invention may be used in other fields where it may be advantageous to use a device similar to that disclosed herein to straddle the work to support and guide it. Therefore, I do not wish to be limited to the details herein set forth, but my invention is of the full scope of the appended claims.

I claim:

1. A steady rest for lathes comprising two sections hingedly connected together and adapted to straddle the work being supported, an extension formed on the lower end of each section and means provided thereon to engage one of a pair of parallel lathe ways, and means on each extension for releasably locking each section to its respective lathe way.

2. A steady rest for lathes comprising two sections hingedly connected together and adapted to straddle the work, means carried by said

sections for steadyng the work, an extension formed on the lower end of each section and having means provided thereon to engage one of the ways of the lathe, and means on each extension for releasably locking each section to its respective lathe way.

3. A steady rest for lathes comprising two sections hingedly connected together and adapted to straddle and support the work being operated on by the lathe, an extension formed on the lower end of each section and guide means provided thereon to engage a pair of parallel lathe ways, and means for releasably locking the steady rest to the lathe ways, whereby upon release of the lock means, the steady rest may be removed and replaced on the lathe ways without disturbing the work on the lathe.

4. In a steady rest for lathes, the combination of a yoke shaped body having a pair of depending legs adapted to straddle a work piece rotatably mounted in the lathe, means on each of said depending legs adapted to contact one of the ways of the lathe, and adjustable guides carried by said body and adapted to maintain the work piece on its rotational axis.

5. In a steady rest for guiding a work piece in a lathe, a yoke shaped body, a pair of depending legs on said body adapted to straddle the work when applied to the lathe, guide means carried by said body for steadyng the work piece, and means for releasably locking the steady rest to the ways of the lathe.

6. A work support for lathes comprising a plurality of sections hingedly connected together and adapted to straddle and support the work when applied to the lathe, two of the sections provided with guide means to engage with the ways of the lathe, and means for releasably locking the work support to the lathe ways, whereby upon release of the lock means, the work support may be removed from the lathe without disturbing the work.

7. In a device of the class described for use in conjunction with a work piece and a support, the combination of a body comprising a plurality of sections movably connected together, two of said sections having depending legs adapted to straddle the work piece, upon the body being moved into its operative position, and means to secure the lower ends of said legs to said support.

8. In a device of the class described for use in conjunction with a work piece and a support, the combination of a body comprising a plurality of sections movably connected together, two of said sections having depending legs adapted to straddle the work piece, upon the body being moved into its operative position, adjustable means carried by said sections adapted to steady the work piece, and means to secure the lower ends of said legs to said support.

9. A steady rest for lathes comprising in combination a plurality of members hingedly connected together and adapted to straddle the work on the lathe, two of the members being provided with guide means thereon, said guide means comprising angle sections adapted to engage with complementary angle sections of the lathe ways, means carried on said members for steadyng the work, said means including guide members located on either side and below the horizontal axis of the work and symmetrically spaced to form an included angle greater than the included angle formed by the inside slopes of the angle sections of the lathe ways, whereby the steady rest may

be removed from the lathe without disturbing the work.

10. A steady rest for lathes comprising two members hingedly connected together and adapted to straddle the work when applied to the lathe, an extension formed on the lower end of each member, means on each extension adapted to engage one of the ways of the lathe, said means including an angle section adapted to engage with 5 a complementary angle section on its respective lathe way, latches for releasably locking each member to its respective lathe way, means on said members for steadyng the work, said means including a vertical guide member and two guide 10 members symmetrically located on either side and below the horizontal axis of the work, the included angle formed by the two lower radial guide members being substantially greater than the included angle formed by the inside slope of the 15 lathe ways, whereby upon releasing said latches the steady rest may be removed from the lathe ways without disturbing the work.

11. In a steady rest for use in conjunction with a work piece and a pair of horizontal parallel 20 ways, the combination of a pair of members pivotally connected together, each member having a depending leg adapted to engage one of said ways, each leg being provided with an angle portion adapted to contact the complementary angle 25 section on its respective way, a plurality of adjustable guides carried on said members and adapted to contact and steady the work piece, two of said guides being positioned on either side 30

of and below the axis of the work piece, the included angle formed between the lines of action of said lower two guides being substantially greater than the included angle formed between the inside slopes of said angle sections of the 5 ways, whereby the steady rest may be removed from the ways without disturbing the work and without changing the setting of the adjustable guides.

12. In a steady rest for use in conjunction with 10 a work piece and a support, the combination of a body comprising a pair of sections movably connected together, said sections having depending legs adapted to straddle the work piece, means to secure the lower ends of said legs to said support, three equally spaced guides carried by said 15 body and adapted to steady the work piece relative to said body, means to adjust said guides radially of said work piece, and means to secure said guides in adjusted position. 20

13. In a steady rest for use in conjunction with a work piece and a pair of parallel ways, the combination of a body, guide means carried on the body adapted to steady the work piece, releasable latch means for securing said body to 25 said ways, said latch means including an element rotatably supported by said body about a certain axis, said element having a portion eccentric with respect to said axis, a latch member rotatably supported on said eccentric portion and adapted 30 to engage a shoulder associated with one of said ways, and means to rotate said element.
